OIL BURNER

Robert F. Andler, Rutherford, N. J., assignor to
 Electrol Incorporated, Clifton, N. J., a corpora-
 tion of Delaware

Application December 29, 1936, Serial No. 118,079

6 Claims. (Cl. 158—76)

My invention relates to apparatus to carry out the steps set forth in my copending application Serial No. 118,081, filed December 29, 1936, in which I have described a process or method of oil burning which consists of forming the air current into a gyrating lamina annulus and then winding it up after it leaves the discharge nozzle so it will form a vortex.

The principal object of my invention is to provide an efficient apparatus for that purpose.

A further object is to locate the means for forming said gyrating lamina annulus inside the chamber and before mixing the oil with it.

A further object is to provide a construction to accomplish the desired result which will be located in the discharge nozzle.

My means of accomplishing the foregoing objects may be more fully comprehended by having reference to the accompanying drawing, which is hereunto annexed and is a part of this specification in which:

Fig. 1 is a front elevation of my improved oil burner a portion being shown in section;

Fig. 2 is a side view of the same, parts of the exterior wall being broken away to show the interior;

Fig. 3 is a detail perspective view of a deflecting disc;

Fig. 4 is a vertical section of a fragmentary portion of the air receiving chamber showing a modified form of deflecting disc;

Fig. 5 is a section taken on the line 5—5 in Fig. 4;

Fig. 6 is a fragmentary detail view of a modified form of deflector disc; and

Fig. 7 is a section taken on the line 7—7 in Fig. 6.

Similar reference numerals refer to similar parts throughout the entire specification.

As shown in the drawing, an electric motor 1 is directly connected to a blower fan 2 of standard construction. The outlet 3 of the fan is connected to a cylindrical sleeve or chamber 4. A tube 5 is provided through which the oil passes to a nozzle through which it is sprayed. This tube may be mounted axially of the chamber.

On this tube 5 I mount a deflector disc 6 which is provided with a plurality of apertures 7 at its periphery. Vanes 8 are cast on or attached to, the disc 6.

In some instances it may be found desirable to have the disc 6 rotatably mounted on the tube which obviously can be done without departing from the scope of my invention.

The discharging end of the sleeve or chamber

4 is formed by an inwardly tapering wall 9. Inside of this inwardly tapering wall 9 I mount a truncated conoidal member 10 which is spaced from the wall 9 thus providing an annular conoidal space for the escape of the air.

The operation of my burner is as follows: The air enters the chamber 4 from the discharge portion 3 of the blower fan as shown by the arrows in Fig. 2 and impinges upon the disc 6 and then escapes through the apertures 7 in a lamina. The vanes 8 direct it into an annulus having a gyrating motion in which form it is discharged from the tapering nozzle with the result that it is formed into a vortex. The oil is sprayed from the end 11 of the tube into this gyrating lamina 15 of air so that it is thoroughly mixed thus attaining a more efficient combustion.

In Figs. 4 and 5 I have shown a disc 13 of different form, in this case, the hub 12 of the disc 13 is concave, while the face of the disc 13 20 against which the air current impinges is convex. A series of vanes 14 are cut or punched from the disc 13 adjacent the periphery thereof. The vanes 14 are bent outwardly or toward the discharge end or nozzle of the chamber 4. This 25 leaves a series of apertures 15 in the disc 13 intermediate the vanes. Although I have described the vanes 14 being integral with the disc this is not necessary but is merely a preferred construction. The vanes 14 should preferably be given 30 a slight inclination as well as a back pitch as clearly seen in the drawing.

The result of this construction is that a lamina annulus of gyrating air will be directed from the apertures 15.

In Figs. 6 and 7 I have shown a plain cone 16 mounted upon the tube 5 with its base towards the discharge nozzle but spaced from the wall of the sleeve or chamber 4. This operates to deflect the air into a lamina annulus.

In order to impart a gyratory motion to this air current I provide a plurality of vanes 17 located in the annular conoidal space intermediate the inwardly tapering wall 9 and the truncated cone 16. These vanes operate to impart a gyratory motion to the air current and wind it up so that it will form a vortex when it leaves the nozzle. It will be clear to persons skilled in the art that the operation of the modified forms of construction are similar to the operation of the one first described.

Having described my invention, what I regard as new and desire to secure by Letters Patent is:

1. In an oil burner, an electric motor, a blower

- fan driven by said motor, a cylindrical conduit closed at one end and open at the other end, means to connect the discharge of the fan to the said conduit adjacent its closed end, an oil supply tube which extends axially in said conduit, a nozzle at the end of said tube to spray oil beyond the open end of said conduit, a disc on said tube between said connecting means and the open end of said conduit, said disc being provided with a plurality of peripheral notches and contacting the wall of said conduit, a plurality of inclined vanes adjacent said notches, said notches and vanes directing the air current into a thin gyrating annulus along the conduit wall, and means at the discharge end of said conduit to contract said gyrating air current and cause it to form a vortex outside of said conduit.
2. In an oil burner, an electric motor, a blower fan driven by said motor, a cylindrical conduit closed at one end and open at the other end, means to connect the discharge of the fan to the said conduit adjacent its closed end, an oil supply tube which extends axially in said conduit, a nozzle at the end of said tube to spray oil beyond the open end of said conduit, a concave disc rotatably mounted on said tube between said connecting means and the open end of said conduit, a plurality of vanes formed on said disc adjacent its periphery, said disc being provided with openings intermediate said vanes, said disc when rotated drawing the air directly into the vanes and thrusting it outwardly in a gyrating annulus along the conduit wall, and means at the discharge end of said conduit to contract said gyrating air current and cause it to form a vortex outside of said conduit.
3. In an oil burner, an electric motor, a blower fan driven by said motor, a cylindrical conduit closed at one end and open at the other end, means to connect the discharge of the fan to the said conduit adjacent its closed end, an oil supply tube which extends axially in said conduit, a nozzle at the end of said tube to spray oil beyond the open end of said conduit, a disc on said tube between said connecting means and the open end of said conduit, said disc having a plurality of vanes adjacent its periphery, said disc being provided with openings intermediate said vanes which direct the air into a thin gyrating annulus along the conduit wall, and means at the discharge end of said conduit to contract said gyrating air current and cause it to form a vortex outside of said conduit.
4. In an oil burner, an electric motor, a blower fan driven by said motor, a cylindrical conduit closed at one end and open at the other end, means to connect the discharge of the fan to the said conduit adjacent its closed end, an oil supply tube which extends axially in said conduit, a nozzle at the end of said tube to spray oil beyond the open end of said conduit, a disk mounted on said tube between said connecting means and the open end of said conduit, said disc being provided with a plurality of peripheral notches, said notches being formed to direct the air current into a thin gyrating annulus along the conduit wall, and means at the discharge end of said conduit to contract said gyrating air current and cause it to form a vortex outside of said conduit.
5. In an oil burner, an electric motor, a blower fan driven by said motor, a cylindrical conduit closed at one end and open at the other end, means to connect the discharge of the fan to the said conduit adjacent its closed end, an oil supply tube which extends axially in said conduit, a nozzle at the end of said tube to spray oil beyond the open end of said conduit, a disk on said tube between said connecting means and the open end of said conduit, said disc being provided with a plurality of peripheral notches, a plurality of inclined vanes adjacent said notches whereby the air current is formed into a gyrating annulus along the conduit wall, the discharge end of said chamber tapering inwardly, a truncated cone mounted inside of said inwardly tapering wall but spaced therefrom and a plurality of vanes mounted in said space, said vanes being inclined in the same direction as the first mentioned vanes, to contract said gyrating air current and cause the air current to form a vortex outside of said chamber.
6. In an oil burner, an electric motor, a blower fan driven by said motor, a cylindrical conduit closed at one end and open at the other end, means to connect the discharge of the fan to the said conduit adjacent its closed end, an oil supply tube which extends axially in said conduit, a nozzle at the end of said tube to spray oil beyond the open end of said conduit, means mounted at the discharge end of said conduit to direct the air into a thin gyrating annulus along the wall of the conduit, and means at the discharge end of said conduit to contract said gyrating annulus and cause it to form a vortex outside of said chamber.

ROBERT F. ANDLER.
